DESIGN FOR A COMBINED RANGE LAMP AND SUPPORT THEREFOR

Ray A. Schober, Chicago, Ill., assignor to Premium
Products Mfg. Co., Chicago, Ill., a partnership

Application April 16, 1940, Serial No. 91,717

Term of patent 3½ years

To all whom it may concern:

Be it known that I, Ray A. Schober, a citizen of the United States, residing at Chicago, in the county of Cook, and State of Illinois, have invented a new, original, and ornamental Design for a Combined Range Lamp and Support Therefor, of which the following is a specification, reference being had to the accompanying drawing, forming part thereof.

Fig. 1 is a front elevational view, slightly in perspective, of a combined range lamp and support therefor, showing my new design.

Fig. 2 is a side elevational view thereof.

Fig. 3 is an inverted plan view of the lamp housing forming a part of the composite design shown in Figs. 1 and 2.

I claim:

The ornamental design for a combined range lamp and support therefor, substantially as shown.

RAY A. SCHOBER.
